AUTOMATIC TUBE DRAWING PRESS

Jean V. Giesler, Knoxville, Tenn., assignor to The
Fulton Sylphon Company, Knoxville, Tenn., a
corporation of Delaware

Application August 15, 1938, Serial No. 225,034

28 Claims. (Cl. 205—4)

This invention relates to automatic tube drawing presses and more particularly to hydraulically operated tube drawing presses in which the various steps of the operation are automatically performed in proper sequence.

Generally the apparatus of the present invention comprises a piston operating one or if desired a pair of oppositely disposed slides each carrying a mandrel and having dies cooperatively arranged with respect to the mandrels, each of the dies having a hopper arranged to feed tube blanks into position to be entered by the mandrel, whereupon the mandrel is then forced through the die to draw the tube blanks in succession, the action of each mandrel being automatic and if a pair are used they operate respectively on opposite strokes.

Heretofore tube drawing presses have been known in which a piston operates a mandrel carrying a tube to be drawn and forces the tube through a die to draw the tube as desired. In these devices many of the steps of operation were of necessity manually controlled and as but one mandrel was operated by the piston the rate of production was relatively low and the standard of production lacking in desirable uniformity due to the human equation of the operator.

It is accordingly one object of the present invention to provide a novel tube drawing press in which the steps of operation are automatically controlled.

Another object of this invention is to provide a novel tube drawing press in which the motion of a piston in both halves of its reciprocatory cycle is utilized to draw a tube.

Another object of this invention is to provide a novel tube drawing press in which the motion of a piston is automatically and hydraulically controlled to effect the drawing of a tube, preferably during both halves of the reciprocatory cycle of the piston.

Another object of this invention is to provide a novel automatic tube drawing press in which a novel carrier is provided to be actuated by a piston and to carry the mandrel.

Another object of this invention is to provide a novel automatic tube drawing press in which novel means are actuated by the piston operating the mandrel or mandrels to flare the open ends of the tube blanks before the mandrel enters the tube blanks.

Another object of this invention is to provide a novel automatic tube drawing press in which novel feeding means are utilized to first hold the tube blanks while their open ends are being flared

and then automatically and in proper sequence in the operating cycle move the tube blanks into position and hold them for engagement with the mandrel.

Another object of this invention is to provide a novel automatic tube drawing press in which novel feeding means are automatically operated hydraulically in proper sequence and in timed relation with the means hydraulically operating the mandrel or mandrels to first hold the tube blanks while their open ends are being automatically flared and then to move the tube blanks into position for and to hold them during engagement with the mandrel.

Another object of this invention is to provide a novel automatic tube drawing press in which a novel die assembly automatically strips the drawn tube from the mandrel at the termination of the drawing cycle.

Another object of this invention is to provide a novel automatic tube drawing press in which novel means are hydraulically and automatically actuated in proper sequence in the cycle to move into engagement with and assist the novel tube blank feeding means in holding the tube blank while it is engaged by the mandrel.

Another object of this invention is to provide a novel automatic tube drawing press in which a novel hydraulic system automatically and in proper timed relation actuates the various operations of my novel press.

Another object of this invention is to provide a novel automatic tube drawing press having a novel automatic hydraulic actuating system which may be manually stopped at any stage of the operating cycle and which will recommence operations at the point where stopped when again manually started.

Another object of this invention is to provide a novel automatic tube drawing press which is simple in construction, durable, efficient, easily operated and inexpensive to manufacture and maintain.

Other objects of the present invention will appear as the description thereof proceeds.

The present invention is capable of expression in many and various mechanical embodiments, one of which is illustrated in the accompanying drawings, but it is to be expressly understood that the drawings are for the purposes of illustration only, and are not to be construed as the definition of the limits of the invention, reference being had to the appended claims for that purpose.

Referring in detail to the drawings, wherein the same reference characters are employed to

designate corresponding parts in the several figures:

Fig. 1 is a front elevation of an illustrative embodiment of the novel tube drawing press of the present invention showing the relative positions of the several parts;

Fig. 2 is a rear elevation of the illustrative embodiment of the present invention shown in Fig. 1 showing in detail the novel automatic hydraulic actuating system;

Fig. 3 is a side elevation of the illustrative embodiment of the present invention shown in Fig. 1 as seen from the right in Fig. 1;

Fig. 4 is a cross sectional view on line 4—4 in Fig. 1 showing in detail the novel tube blank feeding means;

Fig. 5 is a cross sectional view of the die assembly used with the illustrative embodiment of the present invention shown in Fig. 1 showing a tube blank being forced through the die;

Fig. 6 is a cross sectional view of the novel stripper used with the illustrative embodiment of the present invention shown in Fig. 1 shown holding the drawn tube as the mandrel is being withdrawn;

Fig. 7 is a detailed view of the novel stripper used with the illustrative embodiment of the present invention shown in Fig. 1;

Fig. 8 is a perspective view of the novel tube blank conveyor used with the illustrative embodiment of the present invention shown in Fig. 1;

Fig. 9 is a front view of the novel tube blank conveyor shown in Fig. 8;

Fig. 10 is a top view of the novel tube blank conveyor shown in Fig. 8; and

Fig. 11 is a side view of the novel tube blank conveyor shown in Fig. 8 as seen from the right in Fig. 8.

In the several figures 10 is any suitable base for my novel press suitably mounted on legs 11. Mounted on base 10 are uprights 12 and 13 designed to carry between them a cylinder 14 the assembly being secured together by tie bolts 15. Mounted in cylinder 14 is piston 16 having piston rods 17 and 18 secured thereto and passing through suitable stuffing boxes 19 and 20 in the ends of cylinder 14. Secured at opposite ends of base 10 are die housing members 21 and 22. Carried by and extending between upright 12 and die housing 21 are mandrel slide guides 23 and 24 upon which is designed to reciprocate the mandrel slide 25 which is secured to piston rod 17. Mandrel slide 25 carries for reciprocation a mandrel 26. Carried by and extending between upright 13 and die housing 22 are mandrel slide guides 27 and 28 upon which is designed to reciprocate the mandrel slide 29 which is secured to the piston rod 18. Mandrel slide 28 carries for reciprocation a mandrel 30.

Carried on bed 10 between upright 13 and die housing 22 is tube blank feeding assembly generally indicated at 31 and shown in more detail in Fig. 4. As seen in Fig. 4 a hollow bracket 32 is suitably secured to base 10 as by bolts or screws 33 and carries thereon a cylinder 34 within which is reciprocally mounted a piston 35 having a piston rod 36. Secured to bracket 32 are hopper side plates 37 and 38 (Figs. 1 and 2) forming with front plate 39 and sloping rear plate 40 a suitable hopper for the tube blanks to be drawn. Rear plate 40 is suitably shaped as at 41 to form a downwardly directed delivery orifice in conjunction with a guide plate 42 secured between side plates 37 and 38 to allow one tube blank at a time to be fed to the carrier as will be more fully

described hereafter. Rotatably mounted in side walls 37 and 38 is a shaft 43 having fingers 44 secured thereto within the hopper and having a gear 45 mounted thereon outside side wall 37, gear 45 having a one way clutch engagement with shaft 43 to rotate shaft 43 in a clockwise direction only as seen in Fig. 4. Engaging gear 45 is a rack 46 having a downwardly depending arm 47 secured to piston rod 36, as at 48, and secured to a slide bar 49 as by screws or bolts 50, slide bar 49 being reciprocally mounted in track 51 formed in the top of bracket 32 and being designed to pass directly beneath the delivery orifice, above described, of the tube blank hopper.

Suitably secured to slide bar 49 as by screws or bolts 52 is my novel tube blank conveyor generally shown at 53 and shown in more detail in Figs. 8-11. As seen in these figures my novel tube blank conveyor comprises a body member 54 recessed at 55 to form a tube blank receiving pocket having an end 56 against which the closed end of the tube blank is designed to abut and a bottom 57. Body member 54 is further recessed at 58 and has rotatably mounted therein on shaft 59 spring clip base 60 to which are suitably secured spring clips 61 extending upwardly to hold the tube blanks in the tube blank pocket. Base 60 has an extension 62 within which is pivotally mounted as at 63 a rod 64 engaging a suitable spring 65 (Fig. 4) which tends to rotate base 60 and urge spring clips 61 into engagement with the tube blank as shown in Fig. 11.

With reference again to Fig. 4, secured to slide bar 49 for reciprocation therewith and depending through a suitable slot 66 in the top of bracket 32 is arm 67. Passing through arm 67 and secured to bracket 32 is rod 68 having mounted thereon stop nuts 69 and 70 to afford an adjustable stop for the movement of arm 67 to the left as seen in Fig. 4. Threaded through arm 67 and locked in position by lock nut 71 is rod 72 designed to engage bracket 32 to form an adjustable stop for the movement of arm 67 to the right as seen in Fig. 4. Passing through arm 67 and adjustable therewith and secured thereto by nuts 73 and 74 is rod 75 passing through a suitable orifice 76 in base 10 and extending within base 10 where it is secured as at 76' to plate 77. Also secured to plate 77 and extending in the line of rod 75 is plunger 78 passing through the opposite side of base 10 and extending into a suitable dash pot 79. Plate 77 is transversely slotted at 80.

Secured to base 10 as by bolts or screws 81 and 82 and lying generally in the plane of bracket 32 is hollow frame member 83 having formed in its top a suitable track 84 and being slotted as at 85. Mounted transversely in frame member 83 is shaft 86 upon which is rotatably mounted a rocker arm 87 recessed at 88 to embrace plate 77 and moving therewith through pin 89 passing through slot 80. Rocker arm 87 is also recessed at 90 to embrace the depending lugs 91 and 92 secured to slide bar 93 mounted in track 84 and imparting reciprocating movement thereto through pin 94. Mounted on slide bar 93 is tube blank conveyor backer 95 having surfaces 96 and 97 designed to further hold and support the tube blank in said tube blank conveyor. Backer 95 is adjustable by set screw 98.

As above described die housing 22 is mounted on base 10 and is suitably positioned for cooperation with mandrel 30. More particularly with reference to Fig. 5 a tube blank 99 mounted on

mandrel 30 is shown passing through the die assembly. As shown in this figure die housing 22 is centrally recessed at 100, recess 100 being enlarged at 101 and 102 forming annular shoulders 103 and 104. Mounted in recess 101 and held against annular shoulder 103 by clamps 105 is die carrier 106 provided with annular die surface 107. Mounted in recess 102 and held against annular shoulder 104 by stripper plate 108 which is secured to die housing 22 by bolts or screws 109 is die carrier 110 provided with annular die surface 111. Stripper plate 108 is annularly cut away at 112 to receive the stripper 113. Stripper 113 is shown in more detail in Fig. 7 and comprises a three part annular member smaller in diameter than the annular recess 112 made up of wedge shaped sectors 114, 115, 116 each section being circumferentially slotted as at 117 to receive an elastic ring 118 of suitable material such as rubber to hold the sectors together. Member 113 is centrally bored at 119, boring 119 having a smaller diameter than that of the finished tube and being cut away as at 120 (Fig. 5) to form an entering surface for the tube being drawn. Cooling medium is conducted to die surfaces 107 and 111 through conduit 119' bored in housing 22 and nozzle 120.

With reference now to Figs. 2 and 4 means are provided for flaring the open end of the tube blank to facilitate entrance of the mandrel. To flare the open end of the tube blank a cone shaped die 121 is fixed to a projecting shoulder 122 of mandrel slide 29 and is so positioned as to engage the open end of the tube blank when the tube blank is in the conveyor 53 beneath the delivery orifice of the hopper.

Positioned between upright 12 and die housing 21 for cooperation with mandrel slide 25 and mandrel 26 is a tube blank feeding assembly generally indicated at 123 which is the exact counterpart of the tube blank feeding assembly 31 above described in detail and having a cylinder 124 (Fig. 2) the exact counterpart of cylinder 34 (Figs. 2 and 4) in blank feeding assembly 31 as well as the other associated parts above described. Further die housing 21 is the exact counterpart of die housing 22 above described and contains all the elements above described in detail with reference to die housing 22 while mandrel slide 25 is provided with a cone shaped die identical with die 121 of mandrel slide 29.

The hydraulic system for use with the above described apparatus is shown in Figs. 1, 2, and 3. Referring to these figures an hydraulic reservoir 125 is mounted within base 10 and is of suitable size to contain enough fluid to meet the demands of the present invention. From reservoir 125 an intake 126 leads to high pressure pump 127 which is secured to and driven by any suitable electric motor 128 mounted on bed 10. Motor 128 is supplied with electrical energy from any suitable source through a fuse box 129 and conduits 130, an electrical switch 131 (Fig. 1) being provided to start and stop motor 128. From pump 127 a pipe 132 leads fluid under pressure to elbow 133. A pipe 134 leads from elbow 133 to a feed control valve 135 which exhausts into reservoir 125. A gauge 136 connecting with elbow 133 through pipe 137 shows the pressure at elbow 133 while a gauge 138 connecting with pump 127 through pipe 139 shows the pressure at pump 127. From elbow 133 a pipe 140 leads to pressure operated valve 141. A pipe 142 leads from pressure operated valve 141 to three way valve 143 which is preferably a self-contained fluid motor operated valve, while a

pipe 144 leads from pressure operated valve 141 through elbow 145 and pipe 146 back to reservoir 125. Pressure operated valve 141 is controlled by manually operable valve 147 connected thereto by pipe 148 and exhausting through pipe 149 into reservoir 125. From three way valve 143 a pipe 150 leads to one side of cylinder 14 and pipe 151 leads from three way valve 143 to the other side of cylinder 14. From three way valve 143 a pipe 152 connects with pipe 146.

Carried by pump 127 and driven by motor 128 is low pressure pump 153 drawing fluid from reservoir 125 through inlet 154. Fluid under pressure is forced from pump 153 through pipe 155 to pressure operated valve 156. Pressure operated valve 156 exhausts through pipe 157 into reservoir 125. From pressure operated valve 156 is led a pipe 158 closed by a cap 159. From pipe 158 fluid under pressure is led through pipe 160 to pilot valve 161 which controls three way valve 143. From pilot valve 161 a pipe 162 leads to one side of three way valve 143 and pipe 163 leads to the other, pilot valve 161 exhausting into reservoir 125 through pipe 164. Pilot valve 161 is operated by a slide rod 165 slidably mounted in uprights 12 and 13 and having secured thereto fingers 166 and 167 designed to engage operating handle 168 of pilot valve 161. Slide rod 165 is reciprocated by the action of mandrel slides 25 and 29 which contact slide rod 165 during part of their reciprocatory cycle.

From pipe 158 a pipe 169 leads to pilot valve 170. Pilot valve 170 connects to opposite sides of cylinder 124 through pipes 171 and 172 and exhausts into reservoir 125 through pipe 173. Pilot valve 170 is actuated by fingers 174 and 175 secured to rod 176 which in turn is secured to mandrel slide 25, fingers 174 and 175 engaging operating handle 177 of pilot valve 170. From pipe 158 a pipe 178 leads to pilot valve 179. Pilot valve 179 connects to opposite sides of cylinder 34 through conduits 180 and 181 and exhausts into reservoir 125 through pipe 182. Pilot valve 179 is actuated by fingers 183 and 184 secured to rod 185 which in turn is secured to mandrel slide 29, fingers 183 and 184 engaging operating handle 186 of pilot valve 179.

A pipe 187 (Figs. 1 and 2) leads fluid under pressure from any suitable source to conduits 119' and nozzles 120 (Fig. 5) to cool the die surfaces 107 and 111.

With the embodiment of my novel automatic tube drawing press set up as above described and as illustrated in the drawings, to place the same in operation the operator closes the electrical circuit to electric motor 128 by closing switch 131. Motor 128 then rotates pumps 127 and 153. Rotation of pump 127 draws fluid from reservoir 125 through intake 126 and discharges the fluid under pressure into pipe 132, elbow 133 and pipe 134, pressure control valve 135 acting to regulate this pressure by exhausting surplus fluid into reservoir 125. Fluid under pressure passes from elbow 133 into pipe 140 and backs up against pressure operated valve 141 which is normally closed. At the same time rotation of pump 153 draws fluid from reservoir 125 through inlet 154 and discharges it under pressure into pipe 155 from which it passes to pressure control valve 156 which acts to exhaust excessive fluid through pipe 157 into reservoir 125. From pressure control valve 156 fluid under controlled pressure passes into pipe 158 and backs up against cap 159, and enters pipe 160 passing into pilot valve 161. The operator now manually opens valve

147 which allows pressure to bleed from pressure operated valve 141 through pipe 148 and exhaust into reservoir 125 through pipe 149 opening valve 141 and allowing fluid under pressure to pass into pipe 142 and three-way valve 143. Pilot valve 161 is so regulated that fluid under pressure now passes therefrom through pipe 162 into the top of three-way valve 143 operating three-way valve 143 to allow fluid under pressure to pass therefrom into pipe 150 and into the left-hand side of cylinder 15 as seen in Fig. 2.

Fluid under pressure in the left side of cylinder 15 forces piston 16 and piston rod 18 to the right sliding mandrel slide 29 to the right, the fluid in the right side of cylinder 15 exhausting through pipe 151, three-way valve 143, pipe 152 and pipe 146 into reservoir 125. Movement of mandrel slide 29 to the right carries with it rod 185 and fingers 183 and 184 until finger 184 engages operating handle 186 of pilot valve 179 operating pilot valve 179 to allow fluid under pressure to pass from pipe 158 through pipe 178, pilot valve 179 and pipe 180 into the left side of cylinder 34 (Fig. 4) to move piston 35 to the right, the fluid in the right side of cylinder 34 exhausting through pipe 181, pilot valve 179 and pipe 182 into reservoir 125. Viewing the operation from Fig. 4, movement of piston 35 to the right moves piston rod 36 and arm 47 to the right which in turn moves rack 46 to the right rotating gear 45, shaft 43 and fingers 44 in a clockwise direction to insure the feeding of tube blanks to the delivery orifice. Movement of arm 47 to the right moves slide bar 49 to the right and with it the tube blank conveyor 53 carrying a tube blank fed into it at the delivery orifice. Movement of slide bar 49 to the right moves arm 67 to the right and with it rod 75, plate 77 and plunger 78, dash pot 79 acting to cushion the movement of these parts. Movement of plate 77 to the right rotates rocker arm 87 in a counter-clockwise direction moving conveyor backer 95 to the left until it comes into contact with the tube blank conveyor 53, surface 96 of backer 95 contacting spring clips 61 and surface 97 contacting a portion of the upper surface of the tube blank to assist in holding it in the tube blank conveyor 53. Meanwhile mandrel slide 29 has continued its motion to the right in Fig. 2, the movement of tube blank conveyor 53 and backer 95 being so regulated that they contact at least by the time mandrel 30 enters the flared end of the tube blank in the tube blank conveyor 53. Further movement of mandrel slide 29 to the right forces mandrel 30 into the tube blank the closed end of the tube blank abutting the end 56 of the conveyor 53 until the mandrel 30 has completely entered the tube blank. At this time finger 183 on rod 185 engages operating handle 186 of pilot valve 179 so operating pilot valve 179 that fluid under pressure is now supplied from pilot valve 179 through pipe 181 to the right side of cylinder 34 (Fig. 4) moving piston 35 to the left the fluid in the left side of cylinder 34 exhausting through pipe 180, pilot valve 179 and pipe 182 into reservoir 125. Movement of piston 35 to the left as viewed in Fig. 4 moves piston rod 36, arm 47 and rack 46 to the left, rack 46 rotating gear 45 in a counterclockwise direction loosely upon shaft 43 without rotation of shaft 43 and fingers 44. Movement of arm 47 to the left moves slide bar 49 to the left carrying with it tube blank conveyor 53. Movement of slide bar 49 to the left moves arm 67, rod 75, plate 77 and plunger 78 to the left

rotating rocker arm 87 in a clockwise direction moving backer 95 to the right out of engagement with conveyor 53. As conveyor 53 moves to the left and backer 95 moves to the right spring clips 61 in contact with the tube blank on mandrel 30 may yield, rotating base 60 in a clockwise direction as seen in Fig. 4 and anticlockwise as seen in Fig. 11 against the action of spring 65 and allowing the tube blank on mandrel 30 to ride over spring clips 61 and out of conveyor 53. As soon as conveyor 53 has cleared the tube blank on mandrel 30, spring 65 rotates base 60 in a counterclockwise direction as in Fig. 4 and clockwise direction in Fig. 11 moving spring clips 61 back to their normal position. Piston 35 moves to the left until conveyor 53 is under the delivery orifice at which time arm 67 engages stop nut 69 on rod 68 and further movement to the left is prohibited and at the same time a tube blank drops into carrier 53 from the delivery orifice.

Meanwhile mandrel slide 29 has continued its movement to the right moving mandrel 30 with the tube blank mounted thereon to the right into engagement with and through the die surfaces 107 and 111 successively drawing the tube blank out into a tube of the desired length and thickness. As the outer end of the finished tube leaves die surface 111 it engages entering surface 120 of the stripper 113 and moves therethrough expanding elements 114, 115 and 116 against the action of elastic ring 118 as shown in Fig. 5. As the inner end of the finished tube starts through the stripper 113 cone-shaped die 121 carried by shoulder 122 of mandrel slide 29 engages the open end of the tube blank in the conveyor 53 beneath the delivery orifice and as the inner end of the finished tube passes through the stripper 113, die 121 enters the open end of the tube blank flaring the open end thereof. When the inner end of the finished tube has passed through stripper 113 elastic ring 118 brings elements 114, 115, 116 back to their normal position behind the end of the tube as seen in Fig. 6.

As piston 16 moves to the right (Fig. 2) moving mandrel slide 29 to the right as above described, it has likewise moved piston rod 17 and mandrel slide 25 to the right into engagement with the left end of slide rod 165 moving slide rod 165 to the right and as the end of the drawn tube on mandrel 30 passes completely through stripper 113 finger 167 on slide rod 165 engages the operating handle 168 of pilot valve 161 operating it to supply fluid under pressure through pipe 163 to the lower side of three-way valve 143 to operate three-way valve 143 to allow fluid under pressure to pass from pipe 142 through pipe 151 into the right side of cylinder 15 to move piston 16 to the left, the fluid in the left side of cylinder 15 exhausting through pipe 150, three-way valve 143, pipe 152 and pipe 146 into reservoir 125. Movement of piston 16 to the left moves mandrel slide 29 and mandrel 30 to the left, the end of the finished tube on mandrel 30 engaging the stripper 113 and allowing mandrel 30 to be drawn from the finished tube, the finished tube thereafter falling into any suitable conveyor or carton. Movement of mandrel slide 29 to the left moves rod 185 to the left and finger 184 thereon engages operating handle 186 of pilot valve 179 rotating it and placing pilot valve 179 in its original position closing both pipes 180 and 181.

Movement of piston 16 to the left moves piston rod 17, mandrel slide 25 and mandrel 26 to

the left. Motion of mandrel slide 25 to the left carries with it rod 176, fingers 174 and 175 thereon engaging operating handle 177 of pilot valve 170 to supply fluid under pressure to cylinder 124 in exactly the same manner as above described with reference to cylinder 34, feeding assembly 123 and die assembly 21 operating in exactly the same way as above described with reference to feeding assembly 31 and die assembly 22.

As mandrel slide 29 moves to the left, it engages the right end of slide rod 165 moving it to the left until finger 166 engages operating handle 168 of pilot valve 161, at which time the drawn tube on mandrel 26 has passed through the stripper of die assembly 21, operating pilot valve 161 to pass fluid under pressure through pipe 162 to the top of three-way valve 143 to operate three-way valve 143 to allow fluid under pressure to pass from pipe 142 through pipe 150 to the left side of cylinder 15 to move piston 16 to the right moving mandrel slide 25 and mandrel 26 to the right stripping the finished tube from mandrel 26 and starting another cycle of operation.

It will now be apparent that the present invention provides a novel automatic tube drawing press operated by the automatically controlled action of a reciprocating piston drawing a tube in either or both halves of its reciprocating cycle, the piston operating novel mandrel carriers, novel means being actuated by the piston to flare the open ends of the tube blanks before the mandrels enter the tube blanks, and novel feeding means being provided to hold the tube blanks while their open ends are being flared. Then automatically and in proper sequence in the operating cycle, the tube blanks are moved into position and held for engagement with the mandrels, novel means being provided to assist the tube blank feeding means in holding the tube blank during the insertion of the mandrel, and tube blanks are then drawn in novel die assemblies provided with novel means for stripping the drawn tubes from the mandrels, the entire operation being automatic in properly timed sequence and being capable of being manually stopped at any stage of the operating cycle and manually started thereafter recommencing operations at the point where stopped. It is also now apparent that the automatic tube drawing press of the present invention is simple in construction, durable, efficient, easily operated, and inexpensive to manufacture and maintain. While preferably drawing a blank at each stroke in both directions, it is apparent that the blank-feeding and drawing means may be omitted at one end of the machine so that if preferred blanks are drawn in one direction only.

To those skilled in the art changes to or modification of the above described illustrative embodiment of my novel automatic tube drawing press will now be apparent without departure from the inventive concept of the present invention. To determine the scope of the present invention reference should be had to the appended claims.

What is claimed is:

1. In an automatic tube drawing press the combination of a piston, a mandrel operated by said piston, a die cooperatively arranged with respect to said mandrel, a source of tube blanks, means actuated by said piston for removing tube blanks from said source and transferring the same into

alignment with said mandrel, and automatic hydraulic means for reciprocating said piston.

2. In an automatic tube drawing press the combination of a piston, a mandrel operated by said piston, a die cooperatively arranged with respect to said mandrel, automatic hydraulic means for reciprocating said piston, a source of tube blanks, and means automatically operated by the reciprocation of said piston for transferring tube blanks transversely to the axis of said mandrel away from said source and into alignment with said mandrel.

3. In an automatic tube drawing press the combination of a piston, a mandrel operated by said piston, a die cooperatively arranged with respect to said mandrel, automatic hydraulic means for reciprocating said piston and forcing said mandrel through said die, a source of tube blanks, and feeding means automatically operated by the reciprocation of said piston for transferring tube blanks in succession away from said source and into alignment with said mandrel before said mandrel enters said die.

4. In an automatic tube drawing press the combination of a piston, a mandrel operated by said piston, a die cooperatively arranged with respect to said mandrel, automatic hydraulic means for reciprocating said piston and forcing said mandrel through said die, feeding means automatically operated by the reciprocation of said piston to feed tube blanks to said mandrel before said mandrel enters said die and means operated by the reciprocation of said piston to flare the open ends of the tube blanks before the tube blanks are fed to said mandrel.

5. In an automatic tube drawing press the combination of a piston, a mandrel operated by said piston, a die cooperatively arranged with respect to said mandrel, stripping means for said mandrel operatively arranged with respect to said die, automatic hydraulic means for reciprocating said piston and forcing said mandrel through said die and said stripping means, feeding means automatically operated by the reciprocation of said piston to feed tube blanks to said mandrel before said mandrel enters said die, and means operated by the reciprocation of said piston to flare the open ends of the tube blanks before the tube blanks are fed to said mandrel.

6. In an automatic tube drawing press the combination of a piston, a mandrel operated by said piston, a die cooperatively arranged with respect to said mandrel, automatic hydraulic means for reciprocating said piston whereby when said piston is reciprocated said mandrel is forced through said die, a source of tube blanks, transfer means for receiving tube blanks in succession from said source, and means for reciprocating said transfer means between positions in alignment with said source and said mandrel, said transfer means being automatically operated by the movement of said piston.

7. In an automatic tube drawing press the combination of a piston, a mandrel operated by said piston, a die cooperatively arranged with respect to said mandrel, automatic hydraulic means for reciprocating said piston, a hopper for tube blanks, a slide for receiving blanks from said hopper and conveying the same into alignment with said mandrel, and means automatically operated by the reciprocation of said piston to operate said slide.

8. In an automatic tube drawing press the combination of a piston, a mandrel operated by said piston, a die cooperatively arranged with

respect to said mandrel, automatic hydraulic means for reciprocating said piston and forcing said mandrel through said die, a source of tube blanks, transfer means for conveying tube blanks into alignment with said mandrel and means automatically operated by the reciprocation of said piston to feed tube blanks from said source to said transfer means and operate said transfer means before said mandrel enters said die.

9. In an automatic tube drawing press the combination of a piston, a mandrel operated by said piston, a die cooperatively arranged with respect to said mandrel, automatic hydraulic means for reciprocating said piston and forcing said mandrel through said die, transfer means for conveying tube blanks into alignment with said mandrel and automatically operated by the reciprocation of said piston to feed tube blanks to said mandrel before said mandrel enters said die, and means operated by the reciprocation of said piston to flare the open ends of the tube blanks before the tube blanks are fed to said mandrel.

10. In an automatic tube drawing press the combination of a piston, a mandrel operated by said piston, a die cooperatively arranged with respect to said mandrel, stripping means for said mandrel operatively arranged with respect to said die, automatic hydraulic means for reciprocating said piston and forcing said mandrel through said die and said stripping means, transfer means for conveying tube blanks into alignment with said mandrel and operated by the reciprocation of said piston to feed tube blanks to said mandrel before said mandrel enters said die, and means operated by the reciprocation of said piston to flare the open ends of the tube blanks before the tube blanks are fed to said mandrel.

11. In an automatic tube drawing press the combination of a piston, a slide operated by said piston, a mandrel mounted on said slide, a die cooperatively arranged with respect to said mandrel, a source of blanks disposed laterally of the axis of the mandrel, tube blank conveying means mounted to reciprocate between said source and a position in which a blank carried thereby is aligned with said mandrel, and automatic means operated by said slide for reciprocating said piston and operating said conveying means.

12. In an automatic tube drawing press the combination of a piston, a slide operated by said piston, a mandrel mounted on said slide, a die cooperatively arranged with respect to said mandrel, automatic hydraulic means operated by said slide for reciprocating said piston, a source of blanks disposed laterally of the axis of the mandrel, tube blank conveying means mounted to reciprocate between said source and a position in which a blank carried thereby is aligned with said mandrel, and automatic hydraulic means operated by said slide for reciprocating said conveying means.

13. In an automatic tube drawing press the combination of a piston, a slide operated by said piston, a mandrel mounted on said slide, a die cooperatively arranged with respect to said mandrel, automatic hydraulic means operated by said slide for reciprocating said piston and said slide and forcing said mandrel through said die, a source of blanks disposed laterally of the axis of the mandrel, tube blank conveying means mounted to reciprocate between said source and a position in which a blank carried thereby is aligned with said mandrel, means for releasing blanks individually from said source to said conveying

means, and automatic means operated by said slide for operating said releasing and conveying means.

14. In an automatic tube drawing press the combination of a piston, a slide operated by said piston, a mandrel mounted on said slide, a die cooperatively arranged with respect to said mandrel, automatic hydraulic means operated by said slide for reciprocating said piston and said slide and forcing said mandrel through said die, a source of blanks disposed laterally of the axis of the mandrel, tube blank conveying means mounted to reciprocate between said source and a position in which a blank carried thereby is aligned with said mandrel, automatic hydraulic means operated by said slide for reciprocating said conveying means, and means mounted on said slide to flare the open ends of the tube blanks before the tube blanks are fed to said mandrel.

15. In an automatic tube drawing press the combination of a piston, a slide operated by said piston, a mandrel mounted on said slide, a die cooperatively arranged with respect to said mandrel, stripping means for said mandrel, automatic hydraulic means operated by said slide for reciprocating said piston and said slide and forcing said mandrel through said die and said stripping means, a source of blanks disposed laterally of the axis of the mandrel, tube blank conveying means mounted to reciprocate between said source and a position in which a blank carried thereby is aligned with said mandrel, automatic hydraulic means operated by said slide for reciprocating said conveying means, and means mounted on said slide to flare the open ends of the tube blanks before the tube blanks are fed to said mandrel.

16. In an automatic tube drawing press including a piston reciprocating in a cylinder, a mandrel actuated by the piston to force tube blanks through a drawing die, tube blank feeding means for said mandrel and a second piston reciprocating in a cylinder to operate said tube blank feeding means, a source of fluid under pressure, an automatic valve in communication with said source of fluid under pressure and with each side of said first named cylinder, a pilot valve automatically operated by the reciprocation of said first named piston in communication with said automatic valve to operate said automatic valve to control the flow of fluid to each side of said first named cylinder and a second pilot valve in communication with said source of fluid under pressure and with each side of said second named cylinder and operated by the reciprocation of said first named piston to control the flow of fluid to each side of said second named cylinder to operate said tube blank feeding means.

17. In an automatic tube drawing press including a piston reciprocating in a cylinder, a mandrel on each side of and operated by said piston to force tube blanks through a drawing die cooperatively arranged with respect to each mandrel, tube blank feeding means for each mandrel, and a piston reciprocating in a cylinder for each of said tube blank feeding means to operate said tube blank feeding means, a source of fluid under pressure, an automatic valve in communication with said source of fluid under pressure and with each side of said first named cylinder, a pilot valve automatically operated by the reciprocation of said first named piston in communication with said automatic valve to operate said automatic valve to control the flow of

fluid to each side of said first named cylinder and a pilot valve for each of said second named cylinders in communication with said source of fluid under pressure and with each side of said second named cylinders and operated by the reciprocation of said first named piston to control the flow of fluid to each side of said second named cylinders to operate said tube blank feeding means.

18. In an automatic tube drawing press including a piston reciprocating in a cylinder, a slide on each side of and reciprocated by said piston, a mandrel mounted on each of said slides to force tube blanks through a drawing die cooperatively arranged with respect to each 15 mandrel, tube blank feeding means for each mandrel, and a piston reciprocating in a cylinder for each of said tube blank feeding means to operate said tube blank feeding means, a source of fluid under pressure, an automatic valve in communication with said source of fluid under pressure and with each side of said first named cylinder, a pilot valve automatically operated by the reciprocation of said slides in communication with said automatic valve to operate said automatic valve to control the flow of fluid to each side of said first named cylinder and a pilot valve for each of said second named cylinders in communication with said source of fluid under pressure and with each side of said second named cylinders and each operated by the reciprocation of said slide adjacent thereto to control the flow of fluid to each side of said second named cylinders to operate said tube blank feeding means in properly timed relation with the movement of said mandrels.

19. In an automatic tube drawing press the combination of a piston, a mandrel operated by said piston in the reciprocatory cycle of said piston, a die cooperatively arranged with respect to said mandrel, a source of tube blanks, means for feeding tube blanks to said mandrel including means for releasing tubes individually from said source and then transporting the same into alignment with said mandrel, and automatic hydraulic means for reciprocating said piston and actuating said feeding means.

20. In an automatic tube drawing press the combination of a piston, a mandrel operated by said piston in the reciprocatory cycle of said piston, a die cooperatively arranged with respect to said mandrel, automatic hydraulic means for reciprocating said piston, a source of tube blanks, means for feeding tube blanks to said mandrel including means for releasing tubes individually from said source and then transporting the same into alignment with said mandrel, and means automatically operated by the reciprocation of said piston for intermittently actuating said tube feeding means.

21. In an automatic tube drawing press the combination of a piston, a mandrel operated by said piston in the reciprocatory cycle of said piston, a die cooperatively arranged with respect to said mandrel, automatic hydraulic means for reciprocating said piston and forcing said mandrel through said die, a source of tube blanks, and feeding means automatically operated by the reciprocation of said piston to feed tube blanks to said mandrel before said mandrel enters said die, said feeding means including a rotatable member for displacing tube blanks individually from said source and a slide for transporting the displaced tube blanks into alignment with said mandrel.

22. In an automatic tube drawing press the combination of a piston, a mandrel operated by said piston, a die cooperatively arranged with respect to said mandrel, automatic hydraulic means for reciprocating said piston and forcing said mandrel through said die, hydraulically operated feeding means automatically operated by the reciprocation of said piston to feed tube blanks to said mandrel before said mandrel enters said die and means operated by the reciprocation of said piston to flare the open ends of the tube blanks before the tube blanks are fed to said mandrel.

10 23. In an automatic tube drawing press the combination of a piston, a mandrel operated by said piston, a die cooperatively arranged with respect to said mandrel, a source of tube blanks, automatic hydraulic means for reciprocating said piston and forcing said mandrel through said die, and feeding means automatically operated by the reciprocation of said piston to feed tube blanks to said mandrel before said mandrel enters said die, said feeding means including a slide for transporting tube blanks from said source into alignment with said mandrel and means operated by said slide to release a tube blank from said source at each return of said slide to said source.

20 24. In an automatic tube drawing press including a piston reciprocating in a cylinder, one or more mandrels actuated by the reciprocation of the piston to force tube blanks through drawing dies and a source of fluid under pressure, tube blank feeding means for each mandrel for feeding tube blanks to the mandrels before the mandrels enter the drawing dies comprising a hopper having a downwardly directed delivery orifice, a carrier mounted for reciprocation beneath said orifice and a second piston supplied from a source of fluid under pressure and controlled by the reciprocation of the first named piston to reciprocate said carrier.

25. In an automatic tube drawing press including a piston reciprocating in a cylinder, one or more mandrels actuated by the reciprocation of the piston to force tube blanks through drawing dies and a source of fluid under pressure, tube blank feeding means for each mandrel for feeding tube blanks to the mandrels before the mandrels enter the drawing dies comprising a hopper having a downwardly directed delivery orifice, a carrier mounted for reciprocation beneath said orifice, means operated by said carrier for displaying a tube blank from said hopper, and a second piston supplied from a source of fluid under pressure and controlled by the reciprocation of the first named piston to reciprocate said carrier.

26. In an automatic tube drawing press including a piston reciprocating in a cylinder, one or more mandrels actuated by the reciprocation of the piston to force tube blanks through drawing dies and a source of fluid under pressure, tube blank feeding means for each mandrel for feeding tube blanks to the mandrels before the mandrels enter the drawing dies comprising a hopper having a downwardly directed delivery orifice, a carrier having a closed end, an open side and resilient means closing said open side mounted for reciprocation beneath said orifice and a second piston supplied from a source of fluid under pressure and controlled by the reciprocation of the first named piston to reciprocate said carrier.

27. In an automatic tube drawing press includ-

ing a piston reciprocating in a cylinder, one or more mandrels actuated by the reciprocation of the piston to force tube blanks through drawing dies and a source of fluid under pressure, tube blank feeding means for each mandrel for feeding tube blanks to the mandrels before the mandrels enter the drawing dies comprising a hopper having a downwardly directed delivery orifice, a carrier mounted for reciprocation beneath said orifice, a second piston supplied from a source of fluid under pressure and controlled by the reciprocation of the first named piston to reciprocate said carrier and a backer actuated by said second named piston to assist said carrier when the mandrel enters the tube blank in said carrier.

28. In an automatic tube drawing press including a piston reciprocating in a cylinder, one or

more mandrels actuated by the reciprocation of the piston to force tube blanks through drawing dies and a source of fluid under pressure, tube blank feeding means for each mandrel for feeding tube blanks to the mandrels before the mandrels enter the drawing dies comprising a hopper having a downwardly directed delivery orifice, a carrier having a closed end, an open side and resilient means closing said open side mounted for reciprocation beneath said orifice, a second piston supplied from a source of fluid under pressure and controlled by the reciprocation of the first named piston to reciprocate said carrier and a backer actuated by said second named piston to assist said resilient means when the mandrel enters the tube blank in said carrier.

JEAN V. GIESLER.
